RELIEF DUPLICATION

John J. Braund, Washington, D. C.

Application September 24, 1946, Serial No. 698,973

26 Claims. (Cl. 18—19)

1

This invention is directed to duplication of relief and particularly to an improved process and machine which will duplicate relief with a high degree of accuracy. The invention is particularly adapted to the reproduction of relief maps, where precision is an indispensable factor, but is also adapted to duplication of other reliefs of utilitarian and ornamental nature.

The general object of the invention is to produce accurate reliefs economically, and to provide a relatively simple and rapid process, and a low cost, easy-operated machine for this purpose.

A further object of the invention is to accurately reproduce reliefs in thermoplastic sheet material.

Still another object of the invention is to produce topographical relief maps and other profiled objects having indicia correlated with the contour thereof, and to mold article blanks upon which the indicia have first been printed or otherwise inscribed in a manner to secure accurate registry of the indicia and contour and cause the indicia to maintain the same positions transversely after deformation of the blank into profile as before, and this regardless of whether the contour is of regular or irregular shape.

A further object of the invention is to secure uniform heating of thermoplastic sheet material in the production of relief therein so that all areas will be softened to the same degree for molding purposes.

Still another object of the invention is to produce relief in thermoplastic sheet material employing a single mold, through the application of vacuum to the side of the sheet facing the mold while subjecting the exposed face of the sheet to uniform heat.

An important additional object of the invention is to mold areas of different amplitude or elevation of a relief in sheet material in progressive order, beginning with areas of lower amplitude or elevation, and to accomplish this by controlling and progressively varying the operating conditions.

According to my prior Patent No. 2,066,555 granted January 5, 1937, duplicate reliefs are produced by securing a sheet at the edges over a liquid reservoir and deforming the sheet by hot liquid under pressure into an inverted female mold disposed above the sheet. While such procedure has been successful in producing relief with a fair degree of accuracy, the machine required has been found to have been more compli-

2

cated than desirable in construction and awkward to operate, also less accurate in results when molding either ductile metal or thermoplastic non-metallic sheets. The present invention has all the advantages of my prior patented machine and is a definite improvement thereon from the standpoint of procedure, simplified machine construction, and operation, and duplicating accuracy.

It should be explained preliminarily that the mode of heating thermoplastic sheet material for the production of relief therein is a matter of considerable importance. The heat should be uniformly distributed throughout the entire area of a sheet to be molded. Overheating in local areas is likely to result in blisters and warping and produce a defective product. Underheating of areas is at least as serious since molding operation is likely to cause cracks or ruptures and ruin the sheet.

Again, the heat must be carefully controlled as to temperature. It is very easy to overheat a plastic sheet beyond the temperatures appropriate to molding, and also to heat it above its softening point too rapidly. I found the best results are secured by slowly raising the temperature of a thermoplastic sheet and molding relief areas of different amplitude at different temperatures, starting with low relief areas during initial heating and progressively molding areas of higher amplitude, or elevation as the temperature of the sheet increases. This is particularly important in producing relief maps, to secure relatively uniform expansion of the sheet in adjoining areas of different amplitude so that points of the sheet will be expanded vertically without horizontal shifting and remain in accurate registry with corresponding points of the mold matrix. This cannot be done if the sheet is too hot and too soft or unevenly heated, since under such conditions areas of different amplitude of the sheet are likely to mold simultaneously and result in excessive stretching and thinning of the sheet in one area and little or no stretching in an adjoining area. The resulting relief may be inaccurate, and if indicia are present they will be shifted laterally relative to one another and out of correct registry with the relief.

I have found that heat transmission through a dry gas, ordinarily air, is best suited to the production of relief in thermoplastic sheet material. It is within the scope of the invention to employ various modes of heating depending upon the nature of the relief and the degree of precision

required. Radiant heat from a battery of infrared or other electric lamps, or electrical resistor heating units has been employed successfully, but this is recommended only for work not requiring a high degree of perfection. It is difficult to locate the radiant heating means in spaced relation to a blank sheet to be molded and obtain uniform heating through the area of the sheet. Also, the temperature of the sheet is likely to be raised too rapidly, it being difficult to properly control such type heating means.

It is also possible to locate a closed dead air chamber over one side of a thermoplastic sheet and provide electric lamps or other heating means in such chamber in substantially spaced relation to the sheet to secure heating of the sheet by conduction. This mode likewise is recommended only where perfect results are not required since it is subject to the same difficulties as radiant heating above referred to.

I have found that convection heating is most satisfactory, and is the only mode which can be employed successfully where a high degree of precision of relief and the absence of flaws are required, as in the case of relief maps. Circulation of dry steam in a closed chamber over the face of a thermoplastic sheet can be employed with opaque sheet material, but it is likely to result in clouding of a transparent sheet, from slight condensation of steam on the sheet surface. I, therefore, prefer to circulate dry hot air over the sheet. I find, further, that better control of the heating temperature to gradually raise the temperature of a sheet may be secured by constantly supplying fresh air, heating it and circulating it over the sheet, and then following it to escape. If dead hot air is trapped adjacent the face of the sheet circulation is impeded and the temperature of the sheet is likely to be raised too slowly rather than too rapidly.

According to my new process a female mold is provided with the desired relief formed therein. During or after casting of the mold a series of holes are formed at intervals of a few inches, more or less. Such holes will communicate with the deepest and other points of all mold cavities, also with flat areas. Hydrostone, a mixture of plaster of Paris and lime, or other suitable durable plaster, with or without the addition of asbestos fibers to give added strength and quicker cooling after molding, may be used in formation of the mold.

A flat relatively thin sheet of transparent or opaque thermoplastic material will be employed for the relief. Vinylite or other suitable synthetic resins which are durable and non-warping, and which have a relatively low softening point somewhat above 100° F. are preferred. The thermoplastic sheet is preliminarily inscribed for many but not all reliefs, depending on their nature, by printing or otherwise with desired indicia. The blank sheet is then placed on the mold while in hard state and where indicia are present they must be brought into accurate registry with the corresponding points of the relief of the mold. The sheet is firmly secured in sealing contact with a frame surrounding the mold. A very low preliminary vacuum is then applied to the mold side of the sheet before its temperature has been raised up to the softening point, particularly the margins of the sheet beyond the mold, to bring the hard sheet into firm contact with the margins of the mold and insure against warping. This will frequently produce a slight dishing effect over all mold cavities also.

Following these initial preparations a progressive molding operation is carried out. This is accomplished through the simultaneous application of vacuum to the mold side of the sheet and heat to the exposed face of the sheet. Convection heating by circulating warm air over the sheet is preferably employed. Heating gradually raises the temperature of the sheet up to and beyond its softening point. The vacuum is also gradually increased in stages to cause the sheet to first contact the shallower molding surface portions of the mold cavities and thereafter gradually be drawn down into contact with the deepest molding surface portions of the mold cavities. In this manner substantially uniform stretching of the sheet in areas of different elevation is obtained. In this manner, also, registry of the indicia, where present, on the sheet with the corresponding points of the mold cavities is preserved.

When the molding operation has been completed, a matter of about twenty minutes, heating is discontinued and the completed sheet is cooled and set, preferably by circulating cool air over the exposed face of the sheet while maintaining the vacuum to insure accuracy of relief. Cooling is continued until the sheet and the mold are well below the softening point of the sheet, say to 90° F. or below, also a matter of about twenty or twenty-five minutes. The sheet with the relief permanently set therein is then removed from the mold. The process is repeated with successive further sheets until the desired number of duplicates have been obtained. The entire operation requires only about three-quarters of an hour for each duplicate.

The vacuum range and the heating temperature range will vary according to characteristics of the particular synthetic resins of which the sheets are formed. Unless sheets of substantial thickness are employed or reliefs of unusual complication are to be produced neither high vacuum or high temperature is required. For example, in the case of vinylite resin sheets of .015 to .020 inch thickness and having a softening point of about 125° F., the vacuum employed in the preliminary stage may be about one inch, following which a low heat is applied to bring the temperature up to about 100° F. Thereupon the vacuum may be increased to about two inches. When the temperature has further increased up to the softening point of the sheet, about 125° F., the vacuum may be increased to three inches. When the temperature has risen to 150° F. the vacuum may be increased to four inches. Heating may be continued to 175° F. as a sufficient maximum. The vacuum then may be again raised to five inches, which has been found the maximum necessary to produce accurate reliefs under the process in many but not in all cases. During the subsequent cooling stage the maximum vacuum is maintained and broken only after the molded sheet has set fully.

The invention will be understood by reference to the illustrative embodiment of my new machine for carrying out my new process shown in the accompanying drawings and the detailed description following.

In such drawings:

Fig. 1 is a sectional elevation of a relief duplicating machine according to the present invention;

Fig. 2 is a top plan view of the machine shown in Fig. 1;

Fig. 3 is a fragmentary top plan view of a indicia-bearing relief map; and,

Fig. 4 is a fragmentary sectional elevation of a mold with the relief map of Fig. 3 therein.

The invention will be described in its application to the duplication of relief maps. The original of such a map will preferably be formed of ductile sheet aluminum or copper according to the method of my prior Patent No. 1,866,448, granted July 5, 1932. According thereto such a flat metal blank is first printed or otherwise inscribed on its rear face with elevation contour lines and elevation and other legends. Such indicia, likewise land and water areas of different elevation, may be printed in different colors. The map blank is then firmly secured around its margin and placed with its top face down upon a compressible pad and embossed step by step, beginning at the lowest contour line of elevation and progressively pressing the metal to the next succeeding contour line until the highest elevation is reached. This is preferably accomplished with the embossing machine of my prior Patent No. 2,029,651, granted February 4, 1936. Such original relief map is then secured upon a rigid backing, the back side of the elevated areas being filled with Hydrostone or other suitable hardening filler for purposes of reinforcement. A suitable frame is then secured around the original map and a mold matrix is then cast thereon and allowed to harden.

A completed mold matrix produced as just described for making duplicates of the original relief map is indicated at 10 in Figs. 1 and 4. Such mold matrix is provided with a series of holes extending vertically therethrough at the levels of different elevation as illustrated at 11, 12, 13 and 14. The number and spacing of such holes will be determined primarily by the character of the contour in any given case, but in general the holes will be located every few inches and communicate with different elevation levels, but in areas which are flat a substantially greater spacing of the holes is satisfactory. The holes may be formed incident to casting of the mold matrix by securing small pegs to the original map which are removed when the mold matrix has hardened, or they may be formed by drilling following completion of the mold.

It will be understood that mold matrix 10 is a female mold with the points of deepest impression therein representing the points of highest elevation of the map. Such matrix is placed in a rigid frame 15 of my new duplicating machine. As shown in Fig. 1 such frame should be of larger size than the matrix to leave a space between the frame and the sidewalls of the matrix. The frame is provided with a closed bottom wall 16 and the matrix is supported in spaced relation thereto by a series of spacer elements 17 so that there is a continuous space between the matrix and both the bottom and sides of the frame. Frame 15 is supported in horizontal position in any suitable manner, as by means of table 18.

Communicating with the interior of frame 15 is a vacuum line 19 connecting with a vacuum source such as a pump. Also mounted on the frame and communicating with the interior are a vacuum gauge 20 and a bleed valve 21. Coaxial with the upper side of frame 15 is a clamping frame 22 which can be removably secured to the main frame by a series of bolts or other securing elements 23.

Located over the face side of mold matrix 10 is a convection air heating space. As shown in Fig. 1 heating of the air may be accomplished by a battery of infra-red or other suitable electric

lamps 24. Such lamps are supported on a frame 25 in substantially spaced relation above the face of mold matrix 10 so as to avoid hot spots at the molding surface of the matrix. A reflecting hood 26 is associated with the lamps to direct the heated air downwardly towards the mold. Preferably, but not necessarily, such hood extends downwardly to clamping frame 22 to completely close the space over the matrix and provide a hot air chamber 27, thus preventing the uncontrolled escape of heat and enabling the molding operation to be carried out in a shorter time than if an air gap is left between reflector hood 26 and clamping frame 22. Observation and access to the interior of the hood may be provided by a series of transparent hinged windows 28. To insure continuous and uniform circulation ventilators are provided to permit the continuous and controlled discharge of the air flow after passage over the mold. In the present machine windows 28 also serve as such air discharge ventilators, being adjustable to any degree of opening to control temperature. Extending into the interior of the hood is a thermometer 29 to show the interior temperature.

The air heated by lamps 24 is positively circulated by means of an electric circulating fan 30. Preferably, and as shown, such fan will be mounted to circulate air vertically towards the face of matrix 10 from a point substantially removed therefrom, thereby to insure uniform distribution of the air over the entire area of the matrix. In embodiment shown in Fig. 1 an air inlet conduit 31 to bring fresh air in continually from outside is mounted on the top of hood 26. Circulating fan 30 is supported adjacent the upper inlet end thereof on a bracket 32, and the supporting frame 25 for the battery of lamps 24 is secured in conduit 31 below the fan. Mounted on the exterior of conduit 31, or at any other convenient point, are rheostat 33 for varying the speed of fan 30 and electric switch 34 for turning lamps 24 on and off.

Hood 26 and the associate parts just described are mounted for vertical movement relative to the position of mold matrix 10. Any suitable form of mounting may be employed. In the present case a pair of counterweighted cables 35 supported by ceiling-mounted pulleys 36 connect with the upper end of conduit 31 so that the entire reflector hood assembly may be easily raised and lowered. To insure proper registry of hood 26 with frame 15 and 22 the lower end of the hood may be provided with a flange 37 adapted to seat against the upper side of clamping frame 22 and apertured to receive and be secured by bolts 23.

In producing duplicate relief maps with the machine and according to the process described a flat map blank S of Vinylite is printed or otherwise inscribed on its top face with elevation contour lines L, elevation legends E and any other desired symbols, also with different colored areas if desired, all in exact accordance with the original map previously described. The printed map blank S is shown in Fig. 3.

The flat map blank S is then placed in the machine with its printed face down facing the mold matrix 10. Blank S should have a marginal area of at least two inches beyond the mold surface and conform generally to the size of frame 15. Where a series of bolts 23 are used as frame securing means, as shown, the blank can be made small enough to lie within the bolts so as to avoid puncturing the margins of the blank to receive the bolts.

Accurate registry of the contour lines L of map blank S with the corresponding contour portions of the mold matrix is essential. This can be accomplished easily where blank S is of transparent material. When the blank is opaque an identical transparent flat map blank can first be registered with the matrix and a plurality of pin holes punched therethrough into the top of frame 15, following which the transparent blank is removed and registered with the opaque blank S. Corresponding pin holes will be punched through blank S and the blank then placed on the frame over the matrix with the pin holes therein registering with those in the frame. Obviously other expedients can be employed for registering purposes.

With the map blank registered with the mold matrix clamping frame 22 is placed on the blank margin, the hood 26 lowered and bolts 23 inserted through frame 22 and into frame 15 to firmly clamp the margins of the map blank with sealing engagement. During this installing operation vacuum bleed valve 21 should be entirely open or the source of vacuum supplied through line 19 should be cut off. When installation has been completed vacuum is supplied to the interior of frame 15 through line 19. Since the vacuum initially employed will be less than that supplied, valve 21 will first be entirely open, and then closed slightly to supply a low vacuum of about one inch.

By reason of the fact that the vacuum is supplied to the space between the sides of matrix 10 and frame 15 the margins of map blank S are drawn into light engagement with the top margins of the mold inwardly adjacent the edges of the mold. This has been found quite important in preventing subsequent formation of wrinkles in the marginal portions of the map blank which engage such top margins of the mold during the actual molding operation. When vacuum is supplied at this time to the face of the blank opposed to the mold matrix a slight deformation of the blank into the mold cavities frequently is obtained.

Switch 34 is turned on to energize the heating lamps 24 and rheostat 33 is turned up partially to operate circulating fan 30 at only moderate speed. One or more of hinged windows 28 in hood 26 should be open so that fresh air drawn in through conduit 31 is heated by the lamps 24, circulated through hood 26 over the face of sheet S and allowed to escape through open windows 28. In this manner the temperature of the sheet is raised gradually up to and beyond its softening point. As the temperature rises vacuum bleed valve 21 is moved in intermittent stages towards closed position to increase the vacuum acting on the opposite side of the sheet through the holes in mold matrix 10. The temperature of the sheet and the amount of vacuum can be watched through thermometer 29 and gauge 20. The temperature of the sheet can be raised faster or more slowly by regulating rheostat 33 to adjust the speed of the fan and the degree of vacuum can be precisely regulated by adjustment of bleed valve 21.

As previously pointed out a preliminary low vacuum is applied to the sheet before softening commences. It is extremely undesirable to heat the sheet preliminary to being clamped in position and drawn into engagement with the mold by the vacuum. As already further pointed out molding of areas of map blank S of low elevation is carried out after the blank has been raised to

a temperature short of its softening point but at which under the vacuum it can be drawn into contact with shallower mold surface areas of the mold, and each successive area of higher elevation is molded successively into contact with deeper mold surface areas as the temperature of a sheet is brought up to and beyond its softening point by increasing the degree of vacuum in stages. In this manner an area of lower elevation of map blank S is expanded into the corresponding part of the mold and seated against further expansion before an adjoining area of higher elevation is expanded. Areas of maximum elevation will be the last molded, maximum temperature and vacuum being employed for this purpose. All of this will be understood by reference to Fig. 4.

The number of stages in which the vacuum is increased, likewise the amount of increase in relation to the rising temperature of the sheet, will be varied depending upon the character of the relief. A relief which has only small differences in elevation between the minimum and maximum can be completely molded in fewer stages and with less vacuum and temperature and in less time than a relief which has substantial differences in elevation.

After map blank S has been completely molded switch 34 is operated to turn off lamps 24. Rheostat 33 is turned on full to cause fan 30 to rapidly circulate incoming cool air through hood 26 over molding sheet S. At this time hinged windows 28 should be fully open. The vacuum is continued as sheet S gradually cools below its softening point and sets. Cooling is continued at least down to 90° F. and can be carried down to room temperature. When cooling has been completed bleed valve 21 will be open fully to eliminate the vacuum, bolts 23 will be withdrawn, hood 26 and clamping ring 22 raised and the completed relief map sheet S withdrawn from mold matrix 10. A new sheet is then placed in the apparatus and the entire process repeated until the desired number of duplicate relief maps have been obtained. Of course mold matrix 10 may be removed from the vacuum chamber and replaced by a new matrix at any time.

The process herein described will produce relief maps with great accuracy and with elevation lines and other indicia exactly in their proper location, and this even though comparatively high elevations are present. Inasmuch as relief maps required for ordinary purposes are on a comparatively small scale the maximum relief to be molded in the sheet will not exceed one or two inches. However, the process has been found adaptable to successful molding to amplitudes of five inches and more provided the process be carried out by raising the temperature and vacuum very gradually.

The invention has been described in its application to the duplication of relief maps to emphasize its adaptability to precision work. It will be understood, however, that the invention is equally adaptable to molding other types of relief in thermoplastic sheet material, either utilitarian or purely ornamental.

The form of the apparatus herein illustrated and described and the suggested ranges of temperature and pressure are to be taken as only exemplary, all being subject to considerable variation depending upon the nature of the thermoplastic sheet material used and the character of the relief to be produced. The scope of the invention is to be determined by the appended claims.

I claim:

1. A relief duplicating machine comprising a vacuum box having an open side and adapted to support a mold matrix therein adjacent said open side, means for removably securing a blank sheet to be molded in sealing engagement with the box in molding position across the open side thereof, a hooded reflector and hot air heating means overlying the open face of the box coactive to uniformly heat the entire area of a blank when secured to the box, and means for supplying a varying blank molding vacuum interiorally of the box.

2. A relief duplicating machine comprising a vacuum box having an open side and adapted to support a mold matrix adjacent said open side, means for removably securing a blank sheet to be molded in sealing engagement with the box in molding position across the open side thereof, a hood overlying the open side of the box and defining an air chamber, air heating means mounted in said hood, circulating means for circulating air over the heating means and for causing heated air to flow over a blank when in molding position, and means communicating with the interior of the box for supplying a varying vacuum to the mold side of a blank when in molding position.

3. A relief duplicating machine comprising a vacuum box having an open side and adapted to support a mold matrix adjacent said open side, means for removably securing a blank sheet to be molded in sealing engagement with the box in molding position across the open side thereof, a hood overlying the open side of the box and defining an air chamber, air heating means mounted in said hood, air inlet means for admitting fresh air into the hood, a fan for drawing air into the hood through said air inlet means and for circulating air over the heating means and over a blank when in molding position, and means communicating with the interior of the box for supplying a varying vacuum to the mold side of a blank when in molding position.

4. A relief duplicating machine comprising a vacuum box having an open side and adapted to support a mold matrix adjacent said open side, means for removably securing a blank sheet to be molded in sealing engagement with the box in molding position across the open side thereof, a closed hood overlying the open side of the box, means mounting the hood for vertical movement away from the box to permit insertion and removal of blanks, an air inlet in the hood, air heating means and air circulating means mounted in the hood, and air outlet means in the hood, and means communicating with the interior of the box for supplying a varying vacuum to the mold side of a blank when in molding position.

5. A relief duplicating machine comprising a vacuum box having an open side and adapted to support a mold matrix adjacent said open side, means for removably securing a blank sheet to be molded in sealing engagement with the box in molding position across the open side thereof, variable speed air circulating means mounted outwardly of the open side of the box adapted to circulate air over a blank when in molding position, means for heating the air to be circulated regulating means for varying the speed of the circulating means adapted to control and vary the temperature of a blank when in molding position, and means communicating with the interior of the box for supplying a varying vacuum to the mold side of a blank when in molding position.

6. A relief duplicating machine comprising a relief mold matrix having recurrent ports extending therethrough and communicating with the molding surface, a vacuum box having an open side in which the mold matrix is mounted with its molding surface adjacent said open side, means for removably securing a moldable blank of greater size than the mold to the box in molding position across the open side of the box, the box being of greater internal dimensions than the mold matrix so as to provide a closed vacuum space around the mold for supplying vacuum through the mold matrix ports to the underside of the area of a moldable blank overlying the mold matrix and also to supply vacuum to the marginal areas of a moldable blank beyond the mold matrix when such a moldable blank is in molding position, means for supplying vacuum to the interior of the box; means for regulating the amount of vacuum in the box, and means for heating a blank when in molding position and while subject to vacuum.

7. In a relief duplicating machine, a vacuum box having an open side and adapted to removably support a mold matrix therein with the molding surface of the mold facing said open side, means for removably securing a blank sheet to be molded in sealing engagement with the box in molding position across the open side thereof, means for heating the exposed face of the blank, an inlet port in the box for supplying molding vacuum to the box interior, a vent port in the box and an adjustable molding vacuum regulating vent valve connecting with said vent port providing communication between the interior of the box and the atmosphere operable during molding to control and varying the degree of vacuum in the box.

8. A method of producing relief having local areas of different elevation in a blank of thermoplastic sheet material through vacuum and heat which comprises supporting the blank in the hard state against the outermost face surfaces of a female relief mold having multiple local molding surface areas of different depth and with the margins of the blank rigidly secured, uniformly heating the side of the blank away from the mold so as to gradually raise the temperature of the blank and applying vacuum to the mold side of the blank, beginning while the blank is still below its softening point, and as the temperature of the blank rises progressively increasing the vacuum in controlled amount on the mold side of the blank so as to draw the blank into contact with the local molding surface areas of different depth progressively, starting with molding surface areas of lesser depth.

9. A method of producing relief according to claim 8, wherein the applied vacuum is progressively increased in controlled amount in intermittent stages.

10. A method of producing relief having local areas of different elevation in a blank of thermoplastic sheet material through vacuum and heat which comprises supporting the blank in the hard state against the outermost face surfaces of a female relief mold having multiple local molding surface areas of different depth and with the margins of the blank rigidly secured, applying a preliminary low vacuum to the mold side of the blank while still in the hard state only sufficient to draw the blank against the outermost face surfaces of the mold, uniformly heating the side of the blank away from the mold so as to gradually raise the temperature of the blank and as

11

the temperature of the blank rises progressively increasing and controlling the amount of vacuum so as to draw the blank into contact with the local molding surface areas of different depth progressively, starting with molding areas of lesser depth.

11. A method of producing relief having local areas of different elevation in a blank of thermoplastic sheet material which comprises supporting the blank in the hard state against the outermost face surfaces of a female relief mold having multiple local molding surface areas of different depth and with the margins of the blank extending beyond the sides of the mold and rigidly secured in outward spaced relation to the sides of the mold, applying heat to the side of the blank away from the mold so as to gradually raise the temperature of the blank and as the temperature rises applying vacuum in progressively increased controlled amount to the mold side of the blank so as to draw the blank into contact with the local molding surface areas of different depth progressively, starting with molding surface areas of lesser depth, and throughout the blank molding operation holding the rigidly secured margins of the blank beyond the mold by applying vacuum to the mold side of said margins.

12. A method of producing relief having local areas of different elevation in a blank of thermoplastic sheet material through vacuum and heat which comprises supporting the blank against the outermost face surfaces of a female relief mold having multiple local molding surfaces of different depth and with the margins of the blank rigidly secured, heating the blank by continuously circulating a hot dry gas at substantially atmospheric pressure uniformly over the side of the blank away from the mold so as to gradually raise the temperature of the blank and as the temperature of the blank rises applying a vacuum in progressively increased controlled amount to the mold side of the blank so as to mold the blank into contact with the local molding surface areas of different depth progressively, starting with the molding surface areas of lesser depth.

13. A method of producing relief having local areas of different elevation in a blank of thermoplastic sheet material through vacuum and heat which comprises supporting the blank in the hard state against the outermost face surfaces of a female relief mold having multiple local molding surface areas of different depth and with the margins of the blank rigidly secured, applying a preliminary low vacuum to the mold side of the blank, then circulating a hot dry gas uniformly over the opposite side of the blank so as to gradually raise the temperature of the blank and as the temperature rises progressively increasing and controlling the amount of vacuum so as to mold the blank into contact with the local molding surface areas of different depth progressively, starting with the molding surface areas of lesser depth.

14. A method of producing relief having local areas of different elevation in a blank of thermoplastic sheet material through vacuum and heat which comprises supporting the blank in the hard state against the outermost face surfaces of a female relief mold having multiple local molding surface areas of different depth and with the margins of the blank extending beyond the sides of the mold and rigidly secured in outward spaced relation to the sides of the mold, applying a pre-

12

liminary low vacuum to the blank from the mold side both at the margins and throughout the entire mold area, then circulating a hot dry gas uniformly over the opposite side of the blank so as to gradually raise the temperature of the blank and as the temperature of the blank rises progressively increasing and controlling the amount of vacuum so as to mold the blank into contact with the local molding surfaces of different depth progressively, starting with the molding surface areas of lesser depth.

15. A method of producing relief in a blank of the thermoplastic sheet material through vacuum and heat which comprises supporting the blank in the hard state against the outermost face surfaces of a female relief mold and with the margins of the blank rigidly secured, applying a preliminary low vacuum to the mold side of the blank while still in the hard state, heating the side of the blank away from the mold and as the temperature of the blank rises increasing and controlling the amount of vacuum so as to draw the blank into contact with the molding surfaces of the mold.

16. A method of producing relief in a blank of thermoplastic sheet material through vacuum and heat which comprises supporting the blank in the hard state against the outermost face surfaces of a female relief mold and with the margins of the blank extending beyond the sides of the mold and rigidly secured in outward spaced relation to the sides of the mold, applying a preliminary low vacuum to the mold side of the blank simultaneously at the margins and throughout the entire mold area while the blank is still in the hard state, heating the side of the blank away from the mold and as the temperature of the blank rises applying a higher vacuum to the mold side of the blank so as to draw the blank into contact with molding surfaces of the mold.

17. In the method of producing relief in a blank of thermoplastic sheet material, the steps of supporting the blank against the marginal face surfaces of a relief mold with the margins of the blank extending beyond the sides of the mold and rigidly secured in outward spaced relation to the sides of the mold, molding the blank to the contour of the mold, and throughout molding holding the rigidly secured margins of the blank beyond the sides of the mold by applying vacuum to the mold side of said rigidly secured margins.

18. A method of producing relief in a blank of thermoplastic sheet material through vacuum and heat which comprises supporting the blank in the hard state against the outermost face surfaces of a female relief mold and with the margins of the blank extending beyond the sides of the mold and rigidly secured in outward spaced relation to the sides of the mold, applying a preliminary low vacuum to the mold side of the margins of the blank, while the blank is still in the hard state, heating the opposite side of the blank and as the temperature of the blank rises applying a higher vacuum to the mold side of the blank so as to draw the blank into contact with molding surfaces of the mold.

19. A method of producing relief in a blank of thermoplastic sheet material through vacuum and heat which comprises supporting the blank against the outermost face surfaces of a female relief mold and with the margins of the blank rigidly secured, heating the blank by continuously circulating hot dry gas at substantially atmospheric pressure, over the side of the blank away from the mold so as to raise the tempera-

ture of the blank uniformly over the entire mold and simultaneously applying a controlled vacuum to the mold side of the blank to draw the blank underheating into contact with molding surfaces of the mold.

20. A method of producing relief in a blank of thermoplastic sheet material through vacuum and heat which comprises supporting the blank against the outermost face surfaces of a female relief mold and with the margins of the blank rigidly secured, heating the blank by flowing a continuously replenished stream of hot air over the side of the blank away from the mold to gradually raise the temperature of the blank, continuously removing at least a portion of the hot air after flowing over the blank and applying vacuum to the mold side of the heated blank to draw the blank into contact with the molding surfaces of the mold.

21. A method of producing an article having relief and containing correlated visible indicia in accurate registry with the relief which comprises supporting a blank of thermoplastic sheet material inscribed with the correlated indicia and in hard state against the outermost face surfaces of a female relief mold with the indicia of the blank in accurate registry with corresponding points of the relief of the mold and with the margins of the blank rigidly secured, uniformly heating the side of the inscribed blank away from the mold so as to gradually raise the temperature of the blank and applying vacuum to the mold side of the blank, beginning while the blank is below its softening point, and as the temperature of the blank rises progressively increasing the vacuum in controlled amount on the mold side of the blank so as to draw the blank into contact with the relief molding surfaces of the mold of different depth progressively, starting with the molding surfaces of lesser depth, and maintain accurate registry of the correlated indicia with corresponding points of relief of the mold.

22. A method of producing an article having relief according to claim 21 wherein hot air is circulated over the side of the blank away from the mold to uniformly heat and gradually raise the temperature of the blank.

23. A method of duplicating a topographical relief map which comprises supporting a map blank of thermoplastic sheet material inscribed with topographical indicia of the desired map and in hard state against the outermost face surfaces of a female relief mold having the relief of the desired map with the topographical indicia in accurate registry with corresponding points of the mold relief and with the margins of the blank rigidly secured, uniformly heating the side of the blank away from the mold so as to gradually raise the temperature of the blank and applying vacuum to the mold side of the blank, beginning

while the blank is below its softening point, and as the temperature of the blank rises progressively increasing the vacuum controlled amount on the mold side of the blank so as to draw the

5 blank into contact with the relief molding surfaces of the mold of different depth progressively, starting with the molding surfaces of lesser depth, and maintain accurate registry of the topographical indicia with corresponding points of the relief of the mold.

10 24. A method of duplicating a topographical relief map according to claim 23, wherein hot air is circulated over the side of the map blank away from the mold to uniformly heat and gradually raise the temperature of the blank.

15 25. A relief map duplicating machine comprising a vacuum box having an open side and adapted to support a mold matrix therein adjacent said open side, means for removably se-

20 curing a blank sheet to be molded in sealing engagement with the box in molding position across the open side thereof, regulatable means communicating with the atmosphere for continuously flowing a controlled and varying amount of hot air at substantially atmospheric pressure uniformly on the outer face of the blank when in molding position, and means communicating with the interior of the box regulatable to supply a varying vacuum to the mold side of a blank dur-

25 30 ing heating in molding position to draw the blank into the mold.

35 26. A relief duplicating machine comprising a vacuum box having an open side and adapted to support a mold matrix adjacent said open side, means for removably securing a blank sheet to be molded in sealing engagement with the box in molding position across the open side thereof, means communicating with the atmosphere located outwardly of the open side of the box operable to continuously flow hot dry fluid at substantially atmospheric pressure uniformly on the outer face of the blank when in molding position, and means communicating with the interior of the box for supplying a varying vacuum to the mold side of a blank during heating in molding position to draw the blank into the mold.
